(57) **CLAIM**

The ornamental design for "wild bird feeder," as shown and
described.

DESCRIPTION

FIG. 1 is a perspective view of my new wild bird feeder.

FIG. 2 is an exploded perspective view of my new bird feeder
showing lid and perch separated from the main body of said
bird feeder.

FIG. 3 is a left side elevational view of my new bird feeder, the
right side being a mirror image thereof.

FIG. 4 is a front elevational view of my new bird feeder, the
back being a mirror image thereof.

FIG. 5 is a top view of my new bird feeder; and,

FIG. 6 is a bottom view of my new bird feeder.

My bird feeder is characterized by a truncated trapezoidal
shape terminated with an arc shaped trough at the small end
and an arc shaped lid, concentric with the trough, at the big
end. Two opposite faces of the tetrahedron are transparent, the
other two faces adjacent to the transparent faces are opaque
and display cross creases reminiscent of heating ventilation
and air conditioning sheet metal fabrication practice.
